(57) **CLAIM**

The ornamental design for a hook and tapered keeper, as shown and described.

DESCRIPTION

FIG. 1 is a perspective view of the hook and tapered keeper showing my new design, with environmental structure illustrated in broken lines;

FIG. 2 is a bottom plan view of the hook and tapered keeper;

FIG. 3 is a top plan view of the hook and tapered keeper;

FIG. 4 is a front elevational view of the hook and tapered keeper;

FIG. 5 is a rear elevational view of the hook and tapered keeper; and,

FIG. 6 is a first side elevational view of the hook and tapered keeper, this view being a mirror image of the opposing second side elevational view of the hook and tapered keeper illustrated in FIGS. 1-5.
